(57) **CLAIM**

The ornamental design for a weed remover, as shown and described.

DESCRIPTION

FIG. 1 is a top plan view of the weed remover;
FIG. 2 is a right side elevational view thereof;
FIG. 3 is a bottom plan view thereof;
FIG. 4 is a left side elevational view thereof;
FIG. 5 is a front end elevational view thereof;
FIG. 6 is a rear end elevational view thereof; and,
FIG. 7 is a front perspective view of the weed remover.
The broken lines showing of the handle represent the environment of the claimed design, and form no part thereof.
